UNITED STATES PATENT OFFICE.

HUBERT BURG, OF MOLLIKIRCH, GERMANY.

TYPE-WRITING MACHINE.

SPECIFICATION forming part of Letters Patent No. 629,233, dated July 18, 1899.

Application filed June 4, 1897. Serial No. 639,438. (No model.)

To all whom it may concern:

Be it known that I, HUBERT BURG, a subject of the German Emperor, residing at Mollkirch, near Rosheim, in the Province of Alsace-Lorraine, Germany, have invented certain new and useful Improvements in Type-Writing Machines, of which the following is a specification.

My invention relates to improvements in type-writing machines in which the types are provided on the surface of a cylinder to be shifted, rotated, and forced against the paper by the depression of keys; and the object of my invention is to reduce the number of keys of the keyboard to a practical minimum in order to simplify the learning with and operating of the machine and to make it serviceable to the blind. I attain these objects by the means illustrated in the accompanying drawings, in which—

Figure 1 is a front view, and Fig. 2 a top view, of the machine; Fig. 3, a vertical section through line $\alpha\alpha$ of Fig. 2; Fig. 4, a top view corresponding to Fig. 2, the top plate, with the keyboard, being removed; Fig. 5, another vertical section through lines $\alpha\alpha$ of Fig. 2 or Fig. 4, and Fig. 6 a left-hand end view of Fig. 2. Figs. 7 and 8 are views of a modification of my invention hereinafter fully described.

Similar numerals refer to similar parts throughout the several views.

Before referring to the drawings it may be briefly explained in which manner a sufficient number of types are controlled by a small number of keys. To this purpose the keyboard consists of two sections, one for each hand, and each section contains four or five keys, one for each finger, one and the same key belonging to one and the same finger, so that the hands and fingers are stationary in operating the machine. For printing a certain type two fingers, one of the left hand and the other of the right hand, are simultaneously to be depressed. Thus by the combined action of the fingers of both hands by two twenty-five different types can be printed, as hereinafter fully explained. These twenty-five types form a longitudinal section of the surface of the type-cylinder, which contains a plurality of such sections—three, for instance—and by means of a shifting key each

of the said sections can be brought into printing position, the same key of the keyboard then controlling again the twenty-five types of the shifted section. By these means seventy-five different types are controlled by eight or ten keys. However, it will be obvious that the number of the said sections may be increased to four or five and one hundred or one hundred and twenty-five different types printed by the small number of eight or ten keys. In order to increase the work of the machine or to enable the same to print simultaneously common types and characters for the blind, the number of the printing parts may be duplicated, as represented in the drawings, the other parts being indifferently the same in a simplex or in a duplex machine.

Referring now to the drawings, the frame of the machine consists of two side walls 11, a top plate 2, and an upper guide-plate 3, carrying the keys 4 5 6 7 and 8 9 10 11, respectively, and a bottom plate 12, supporting the paper-carriages 13 14 and the platens 15 16. The type-cylinders 17 18 project from both sides of the side walls 11, between which the mechanism for rotating, shifting, and depressing the cylinders is provided. The latter are fixed to the ends of a shaft 19, to be shifted and rotated in bearings of a rocking lever-frame 20 21, which is mounted on a shaft 22, journaled in the side frames 11. Another rocking frame 23 24 is loosely mounted on shaft 22 by means of a sleeve 25, and likewise loosely mounted thereon by means of a sleeve 28 is a lever 27, carrying on its free end a toothed segment 26. Frame 20 21 and lever 27 are pressed upward by the springs 29 and 30, coiled on shaft 22 and sleeve 28, respectively. Frame 23 24 bears against lever 27 by means of a pawl 31, pivoted to the outside of the frame-lever 23, and is therefore likewise supported by spring 30. A hook-shaped pawl 32 is pivoted to the frame-lever 23, the upper projection of the pawl bearing on one side against a pin 33 of lever 28 and on the other side against a stop-pin 34, projecting downward from plate 2, thus stopping the rising movement of lever 27 and of frame 23 24. A two-armed cam-lever 35 36, pivoted to the frame-lever 23, bears against lever 27 with the cam portion 35, the upper arm 36 being connected to a rod 37 (partially broken away

in the drawings) and by means of this rod connected to a lever 38, mounted on a shaft 39, which is journaled in bearings on the upper side of plate 2. Another lever 40 is mounted 5 on shaft 39 within the reach of the right-hand thumb and serves for turning lever 35 36, so as to swing downward lever 27. According to the measure of this turning movement pawl 31, actuated by a spring 41, is thereby 10 slipped beyond the steps 42 or 43 on the inside of the segment 26, and when releasing thumb-lever 40 lever 27 rises again, but is stopped by step 42 or 43. In order to disengage pawl 31 from step 42 or 43, a thumb-piece 44, Figs. 1 and 2, is provided within 15 the reach of the left-hand thumb, projecting from a slide 45, which is guided on plate 2 and reaches, with a lateral projection 46, beyond an upper arm 47 of pawl 31, projecting 20 through a slot of plate 2. Slide 45 is actuated toward the right hand of Fig. 2 by a spring 48, so as to be generally kept out of engagement with arm 47; but when the thumb-piece 44 is actuated arm 47 is pressed toward 25 the left, so as to disengage pawl 31 from step 42 or 43, and lever 27 swings back into its normal position with reference to frame 23 24, as shown in the drawings.

The rocking movement of lever 27 is imparted to a pinion 49, fixed to the type-cylinder shaft 19 and engaging with the toothed segment 26 of lever 27. By these means the type-cylinders 17 18 are accordingly rotated.

Supposing now, for instance, fifteen longitudinal rows of types be provided on the surface of the type-cylinder, each row containing five types, and designating the lowermost row in the drawings—*i. e.*, the printing row—as the first row, it will be clear that the first 35 row is in printing position when pawl 31 bears against lever 27 and that the sixth and eleventh rows are brought into printing position when pawl 31 engages with step 42 and 43, respectively, every five consecutive longitudinal 40 rows of types forming one of the above-mentioned sections—*viz.*, rows one to five the first, rows six to ten the second, and rows eleven to fifteen the third section. The type-cylinder, having been shifted to one of the said sections 45 by actuating thumb-piece 40, must further be adjusted to keep five different positions, so as to bring the several rows of each section into printing condition. The first position is immediately given by shifting the several sections as described, while the four remaining 50 positions are afforded by actuating the keys 8 9 10 11 of the right-hand keyboard-section. Keys 8 to 11 are guided in slots of plates 2 and 3 and kept in raised position by coiled 55 springs 50, bearing against shoulders of the reduced portions of the key-stems, the upward movement of springs 50 being limited by plate 3. The key-stems are recessed at their lower ends, showing two steps 51 and 60 52, and frame 23 24 is provided with cross-pins 53 underneath the steps 51. Thus each 65 key when depressed takes along with the

rocking frame 23 24 and likewise lever 27 by means of pawl 31, while the lever-frame 20 21, which carries the type-cylinders, is caught against movement by a catch 55, loosely mounted on the connecting-rod 54 and extending through a slot or plate 2, connecting the frame to that plate. Lever 27 therefore by means of the toothed segment 26 will impart a turning movement to shaft 19, and as the keys have different distances from rocking shaft 22 lever 27 will perform different strokes by depressing the several keys, although the latter are to be uniformly depressed. Thus by conveniently distancing the several parts with reference to the rocking shaft 22 the keys 8 9 10 11 will control the second, third, fourth, and fifth row of each type-section, respectively, so as to bring the same into printing position opposite to the platen.

In order to intercept the momentum of the swinging lever 27 and the type-cylinders, which otherwise would disconnect lever 27 from frame 23 24, thus prejudicing the exact adjustment of the type-cylinders and affording a slurry print, the above-mentioned hook-shaped pawl 32 is provided, which being instantaneously released from pin 34 as frame 23 24 begins to descend is forced by a spring 56 against a piece 60, fixed to the toothed segment 26, and caused to engage with one of the steps 57 58 59, provided on its edge, thus firmly connecting lever 27 to frame 23 24 in accordance with the adjusted type-sections of the type-cylinders. By means of pin 34 pawl 32 is disconnected from piece 60 in the raised position of frame 23 24, thus allowing of a free movement of lever 27 for adjusting the type-sections, as described. Lever 27 and frame 23 24 being firmly connected to each other when performing their swinging movement, so as to prevent any inconvenience arising otherwise from the disconnection of the said parts, it might be desirable for the same purpose to connect the same with the keys, as represented in Fig. 3 with reference to key 11. A hook-shaped pawl 11' is pivoted to key 11 and a projection 12' provided at its upper end, so as to bear against plate 2 when the key is in its raised position, as shown, and release the corresponding cross-pin 53 of frame 23 24 from the hook 11', thus allowing of a downward-swinging movement of the said frame by depressing any one of the other keys; but as soon as key 11 is depressed projection 12' is deprived of its abutment, and the hook by the pressure of a spring 14', intercepting cross-pin 53, firmly connects the entire swinging system to the key. As soon as by depressing a key the corresponding row of types is adjusted in printing position catch 55 is instantaneously released and frame 20 21 taken along with when further depressing the key until the cylinders reach the platens and the printing is performed. This is effected by a lever 61 on a shaft 61^x, journaled in the frame-

walls 1 1, provided with lateral projecting pins 62 underneath the steps 52 of the key-stems, the free end 63 of the said lever engag-
 5 eging with a pin 64 of catch 55. When de-
 pressing a key, first the adjusting movement
 of the type-cylinders takes place, and then
 lever 61 is taken along with as soon as step
 10 52 of the key-stem reaches the corresponding
 pin 62 underneath that step—that is to say,
 immediately before the corresponding row of
 types of the type-cylinders reaches its print-
 15 ing position. In the same time lever end
 63, actuating pin 64 of catch 55, will discon-
 nect the catch and frame 23 24 from plate
 20 2 and strike a collar 66, provided on connect-
 15 ing-rod 54. The several coacting parts are
 calculated and distanced in such manner that
 lever end 63 strikes collar 66 just the same
 20 moment as the adjusting of the type-cylin-
 ders is finished. In consequence thereof
 when further depressing the key no further
 25 turning movement of the type-cylinder takes
 place, as the entire system consisting of the
 parts 20 21 27 23 24 61 then forms an inte-
 gral system, swinging integrally against the
 30 platens to reach the same and perform the
 printing. In order to make the said integral
 system a rigid system within the swinging
 period, so as to eliminate any irregularity
 35 possibly arising from the uncontrolled con-
 nection between lever 61 and frame 20 21,
 there is no difficulty to provide a catch at the
 end 63 of lever 61, coacting in the same man-
 ner with connecting-rod 54 as catch 11' with
 40 the corresponding cross-pin 53. The said
 modification has not been represented, as it
 will be clear from the drawings and descrip-
 tion with respect to catch 11' and its working.

The types provided in longitudinal rows on
 45 the surface of each type-cylinder form in the
 same time five circular sections, as represent-
 ed in the drawings. In order to print a certain
 type, the cylinder besides being turned must
 therefore be longitudinally shifted. This is
 50 effected by the keys 4 5 6 7 of the left-hand
 section of the keyboard, one of which keys
 (key 4) being shown depressed, and the type-
 cylinders shifted in correspondence therewith
 to the largest extent. Two disks 67 68 are
 55 mounted on the type-cylinder shaft 19, and
 pin 69 of a lever 71, mounted on a shaft 70,
 enters the space between the said disks.
 Thus by rocking shaft 70, as hereinafter de-
 scribed, the type-cylinders will be longitudi-
 60 nally shifted and allowed of swinging toward
 the platens without leaving their position ad-
 justed by the shifting movement.

Shaft 70 is journaled in bearings under-
 65 neath plate 2 and rigidly connected to a se-
 ries of levers 72, belonging each to one of the
 keys 4 5 6 7. The latter are guided in the
 plates 2 and 3 and controlled by coiled springs
 74, as described with reference to keys 8 9 10
 11. The stems of keys 4 5 6 7 are recessed
 75 at 75 at their lower ends, Fig. 6, and levers
 72, provided with small rollers 73, enter the
 said recesses when the keys are depressed.

By these means when depressing a key a rock-
 ing movement is imparted to shaft 70 and the
 extent of this movement in the same time 70
 stopped by the roller 73 coacting with the cor-
 responding edge of the recess, as clearly
 75 shown in Fig. 6. In order to exactly limit
 the rocking movement corresponding to each
 key, abutments 76 are provided underneath
 plate 2 in the path of each key-stem, the ob-
 lique edges of which form abutments to bear
 80 against the tapered ends of the stems when a
 key has been depressed, as represented in
 Fig. 6 with respect to key 4. A coiled spring
 77, Fig. 4, presses the lever 71 and the type-
 cylinder shaft 19 to the left of Fig. 6, so as to
 85 keep the first—i. e., the outmost right-hand—
 type-section in printing position if no key is
 depressed. The shifting of the second, third,
 fourth, and fifth sections is then performed
 by depressing the keys 5 6 7 4, respectively.

In order to exactly control the turning and
 shifting adjustment of the type-cylinders, the
 well-known correcting-wheel 19^X on shaft 19 90
 and a correcting-plate 20^X of the base-plate
 12 is made use of. Before the cylinders reach
 the platens the upper edge of plate 20^X enters
 the opposite notch of wheel 19^X, thus con-
 trolling the turning adjustment immediately 95
 before the printing is performed, and as the
 edge of plate 20^X is provided with notches
 21^X, corresponding to the several longitudinal
 positions of wheel 19^X, it will be clear that the
 wheel engaging with plate 20^X is in the same 100
 time longitudinally adjusted.

The letter-space shifting of the paper-car-
 riages may be brought about by the oscilla-
 105 tory movement of frame 20 21, as represented
 in Figs. 3, 4, and 5. A horizontal shaft 80 is
 journaled in bearings 78 79, carrying a ratchet-
 wheel 81 and two gear-wheels 82 83, the lat-
 110 terer engaging with racks 86 87 of the carriages
 13 14, which are guided on rails 88 89 of the
 bottom plate 12. Shaft 80 is driven, as indi-
 cated by arrow 85, Fig. 3, by means of a clock-
 spring provided in a spring-box 84. A hori-
 115 zontal rocking shaft 90 extends between the
 bearings 78 79, carrying a lever 91 and a two-
 armed ratchet-lever 92 93, and is actuated by
 a spring 94. Lever 91 lies in the path of
 frame-lever 20, and when actuated by the
 120 rocking of frame 20 21 ratchet-wheel 81 will
 be rotated step by step in the well-known
 manner and the carriages accordingly shifted.
 The hook-shaped part 95 of lever 93 is con-
 125 nected thereto by a spring-piece 93' in order
 to allow of passing of the ratchet-teeth of
 wheel 81 underneath hook 95 as the carriages
 are shifted by hand to their initial position.

An inking device is represented, Figs. 1 and
 2, in connection with one of the two type-
 cylinders. Reels 96 97, provided with sleeves
 98 99, are loosely mounted on pins 100 101,
 laterally projecting from the side walls 1 1, 130
 and ratchet-wheels 102 103, fixed to the other
 ends of the said sleeves. The ink-ribbon 104
 passes from reel 96 to reel 97 and is guided
 on a jacket 105, fixed to the side wall and

partially surrounding the type-cylinder 17. The jacket is open at the bottom for the passage of the type-cylinder, and when the latter swings toward the platen the printing is performed by the medium of the ribbon part 106. The ink-ribbon is shifted by a lever 107, mounted on the outer end of rocking shaft 22 by means two pawls 108 109, pivoted to lever 107 and engaging with the ratchet-wheels 102 103, respectively. The pawls bear against two eccentrics 111 112 on a pin journaled in the side wall 1 and adjustable by a handle 110, and the eccentrics are in such relative position to each other that by conveniently turning the handle 110 pawls 108 and 109 can be alternately engaged with ratchet-wheels 102 and 103, respectively, or disengaged therefrom.

The word-spacing is performed by a key 113, Figs. 1, 2, and 4, mounted on the outer end of the shaft 61^X of lever 61. By depressing key 113 lever 61 is actuated and takes along with frame 20 21, as heretofore explained, and likewise frame 23 24 is taken along with by the medium of the cross-pins 53, against which the descending lever 61 strikes. In consequence thereof the lever and frame system is integrally rocked, no turning movement of the cylinders taking place.

In order to prevent hereby the printing of a type, as required, for the word-space, the corresponding parts of the type-cylinder surfaces are left without types and depressed with respect to the proper printing-surface. The ink-ribbon therefore cannot reach the paper, and the latter is left blank. It will be obvious that key 113 is likewise to be actuated by the right hand whenever types of the several first longitudinal rows of the longitudinal type-sections are to be printed.

The second (rear side) printing device may likewise be provided with an ink-ribbon or left without any inking apparatus if it shall be utilized for producing raised characters for the blind by means of a punching-cylinder, as well known.

Although the machine is represented in the drawings in connection with two printing devices, there will obviously be no difficulty to restrict the same to but one without departing from the invention. It will likewise be obvious that the shifting device for shifting the several longitudinal sections can be restricted to but two sections or extended to more than three sections without any departure from the invention.

If in the case of providing two printing devices, one for common types and the other for characters for the blind, it should be desirable to have the latter highly raised, I prefer the modification of the invention represented in Fig. 7, part of the front view, and Fig. 8, full side view, in which the type or printing cylinders perform different strokes, as appearing from Fig. 8. In this modification the only difference consists in that the lever-frame 20 21 of Fig. 3, which carries the type-cylinders,

is modified to form a swinging box 114, Fig. 7, front view, while all the other parts admit of no change. In the said box are provided the unchanged former parts 22, 23, and 24, 26 and 27, 61 and 61^X, as represented, and likewise the parts 70, 71, and 72 and keys 4 5 6 7 8 9 10 11, not represented in the drawings, as they are of no importance to explain the modification. The working of the said parts is likewise the same as heretofore described. Shaft 19, with the type-cylinders and the others parts supported by that shaft, and catch 55 are likewise journaled in box 80 114, the latter, as stated before, supplying the place of former swinging frame 20 21. Box 114 is supported by lateral arms 115, mounted on a rocking shaft 117, which extends between uprights 116, secured to the base-plate 85 12, and is kept in its raised position by a coiled spring 118, its upward swinging movement being controlled by pins 119 of the uprights and pins 120 of the arms 115, bearing against pins 119. A post 121 is secured to base-plate 12, extending throughout box 114, and, passing through a slot in its cover-plate and box 114, is caught in its raised position by catch 55, intercepting the upper edge of the said post. As soon as the catch is released by depressing one of keys 8 9 10 11 or key 113, as heretofore described, box 114 is swung toward the platens, the right-hand cylinder of Fig. 8 thereby obviously performing a larger stroke than the left-hand cylinder. If, therefore, the former contains the characters for the blind and the latter common types, it will be clear that without derogating from the quality of the common letters highly-raised characters for the blind are to be obtained.

Having now particularly described and ascertained the nature of my said invention and in what manner the same is to be performed, I declare that what I claim is—

1. In a type-writing machine, in which the types are arranged on the surface of a swinging cylinder, the combination of two sets of keys, one set for shifting, and the other for rotating the type-cylinder, a swinging arm or frame to be struck by the rotating keys, a support for the type-cylinder pivoted to the rock-shaft of the said arm or frame, an adjustable segment likewise pivoted to the said rock-shaft and engaging with a pinion on the type-cylinder shaft, a pawl pivoted to the swinging arm or frame and engaging with ratchet-teeth of the segment, and means for disengaging the pawl, substantially as and for the purposes described.

2. In a type-writing machine, in which the types are arranged on the surface of a swinging cylinder, the combination of two sets of keys, one set for shifting and the other for rotating the type-cylinder, a swinging arm or frame to be struck by the rotating keys, a support for the type-cylinder pivoted to the rock-shaft of the said arm or frame, an adjustable segment likewise pivoted to the said

rock-shaft and engaging with a pinion on the type-cylinder shaft, a cam-lever pivoted to the swinging arm or frame and striking the arm of the segment, and means for actuating 5 the cam-lever, substantially as and for the purposes described.

3. In a type-writing machine, in which the types are arranged on the surface of a swinging cylinder, the combination of two sets of 10 keys, one set for shifting and the other for rotating the type-cylinder, a swinging arm or frame to be struck by the rotating keys, a support for the type-cylinder pivoted to the rock-shaft of the said arm or frame, an adjustable segment likewise pivoted to the said rock-shaft and engaging with a pinion on the type-cylinder shaft, a pawl pivoted to the swinging arm or frame and engaging with ratchet-teeth of the segment, a cam-lever likewise pivoted to the swinging arm or frame and striking the arm of the segment, means 15 for disengaging the pawl, and means for actuating the cam-lever, substantially as and for the purposes described.

25 4. In a type-writing machine, in which the types are arranged on the surface of a swinging cylinder, the combination of two sets of keys, one set for shifting and the other for rotating the type-cylinder, a swinging arm or 30 frame to be struck by the rotating keys, a support for the type-cylinder pivoted to the rock-shaft of the said arm or frame, an adjustable segment likewise pivoted to the said rock-shaft and engaging with a pinion on the type-cylinder shaft, a pawl pivoted to the swinging arm or frame and engaging with a set of ratchet-teeth of the segment, a catch pivoted to the swinging arm or frame to engage with another set of ratchet-teeth of the 35 segment and to intercept its momentum, and means for disengaging the said pawl and the said catch, substantially as and for the purposes described.

5. In a type-writing machine, in which the types are arranged on the surface of a swinging cylinder, the combination of a swinging frame carrying the type-cylinder shaft, two sets of keys, one for shifting and the other for rotating the type-cylinder, means for 45 shifting and rotating the type-cylinder by simultaneously depressing a shifting and a rotating key, a catch connecting the type-cylinder frame to a stationary part of the machine, and means for releasing the catch by 50 the key stroke, substantially as and for the purposes described.

6. In a type-writing machine, in which the types are arranged on the surface of a swinging cylinder, the combination of a swinging frame carrying the type-cylinder shaft, two sets of keys, one set for shifting, and the other for rotating the type-cylinder, means for shifting and rotating the type-cylinder by simultaneously depressing a shifting and a 60 rotating key, a catch connecting the type-cylinder frame to a stationary part of the machine, means for releasing the catch by the

key stroke, and means for swinging the type-cylinder frame by the key stroke, substantially as and for the purposes described. 70

7. In a type-writing machine, in which the types are arranged on the surface of a swinging cylinder, the combination of a swinging frame carrying the type-cylinder shaft, two sets of keys, one set for shifting and the other for rotating the type-cylinder, means for shifting and rotating the type-cylinder by simultaneously depressing a shifting and a rotating key, a catch connecting the type-cylinder frame to a stationary part of the machine, a swinging lever actuated by the key stroke, releasing the said catch and striking the type-cylinder frame, a catch pivoted to the swinging lever to engage with the type-cylinder frame and to intercept its momentum, and means for releasing the said catches, substantially as and for the purposes described. 75 80 85

8. In a type-writing machine, in which the types are arranged on the surface of a swinging cylinder, the combination of a swinging frame carrying the type-cylinder shaft, two sets of keys, one set for shifting, and the other for rotating the type-cylinder, means for shifting and rotating the type-cylinder by simultaneously depressing a shifting and a rotating key, a catch connecting the type-cylinder frame to a stationary part of the machine, a swinging lever actuated by the key stroke, releasing the said catch and striking the type-cylinder frame, a catch pivoted to the swinging lever to engage with the type-cylinder frame and to intercept its momentum, catches pivoted to the keys to engage with the said swinging lever to intercept the momentum of the entire swinging system, and means for releasing the said catches, substantially as and for the purposes described. 90 95 100 105

9. In a type-writing machine, in which the types are arranged on the surface of a swinging cylinder, the combination of two sets of keys, one set for shifting, and the other for rotating the type-cylinder shaft, means for shifting, rotating and swinging the type-cylinder by simultaneously depressing a shifting and a 110 rotating key, a swinging arm or frame to be struck by the rotating keys, a swinging segment engaging with the said arm or frame and with a pinion on the type-cylinder shaft, another swinging frame carrying the type-cylinder shaft, means for connecting to each other the swinging parts in their swinging movement, and means for disengaging the said connections, substantially as and for the purposes described. 115 120 125

10. In a type-writing machine, in which the types are arranged on the surface of a swinging cylinder, the combination of two sets of keys, one set for shifting, and the other for rotating the type-cylinder, a rocking shaft 130 provided with fixed levers to be actuated by the shifting keys, recesses provided at the under side of the shifting keys, and pins or rollers secured to the rocking levers and fit-

ting in the said recesses, substantially as and for the purposes described.

11. In a type-writing machine, in which the types are arranged on the surface of a swinging cylinder, the combination of two sets of keys, one set for shifting, and the other for rotating the type-cylinder, a rocking shaft provided with levers to be actuated by the shifting-keys, recesses provided at the under side of the shifting-keys, pins or rollers secured to the rocking levers and fitting in the said recesses, and abutments to bear against the tapered ends of the keys, substantially as and for the purposes described.

12. In a type-writing machine the combination of a swinging frame carrying a pair of type-cylinders mounted on the same shaft, two sets of keys, one set for shifting, and the other for rotating the type-cylinders, a swinging arm or frame to be struck by the rotating keys, a support for the type-cylinder pivoted to the rock-shaft of the said arm or frame, an adjustable segment likewise pivoted to the rock-shaft and engaging with the pinion on the type-cylinder shaft, means for adjusting

the segment with respect to the said swinging arm or frame, and means for simultaneously shifting, rotating and swinging the type-cylinders, substantially as and for the purposes described.

13. A type-writing machine, consisting of a swinging frame mounted on a rocking shaft at the rear of the frame, a type-cylinder shaft journaled in the front end of the swinging frame and crossing the direction of the rocking shaft, a pair of type-cylinders mounted on the type-cylinder shaft, two set of keys provided at the top of the swinging frame, one set for shifting, and the other for rotating the type-cylinders, and means for shifting and rotating the type-cylinders and swinging the frame by depressing the keys, substantially as and for the purposes described.

In witness whereof I have hereunto signed my name in the presence of two subscribing witnesses.

HUBERT BURG.
